UNITED STATES PATENT OFFICE.

JAMES MIRREY, OF EAST BOLDON, ENGLAND, ASSIGNOR TO A. REYROLLE & COMPANY LIMITED, OF HEBBURN-ON-TYNE, ENGLAND, A COMPANY OF GREAT BRITAIN.

METAL-CLAD ELECTRIC SWITCH GEAR.

Application filed September 3, 1925. Serial No. 54,347.

To all whom it may concern:

Be it known that I, JAMES MIRREY, subject of the King of England, residing at East Boldon, in the county of Durham, England, have invented certain new and useful Improvements in Metal-Clad Electric Switch Gears, of which the following is a specification.

This invention relates to metal-clad electric switchgear of the draw-out type and has particular reference to switchgear for use with duplicate busbars.

In one well known gear the main oil-break switch which forms part of the movable or draw-out portion of the gear can be connected to either busbar by a plug which can be removed and inserted when the main switch is open and the movable portion of the gear drawn out.

It is also known to provide plug connections which can be inserted and removed into and from the busbar sockets through openings passing right through the hood or casing of the movable portion, this operation of the plugs thus being possible without moving the casing. In such a construction means have been suggested for preventing the removal of the plug until the main switch has been opened.

In switchgear of the type in which the main switch can be moved vertically relative to the busbar portion above it a special construction of the main switch has been proposed to enable either or both of the duplicate busbars to be placed in service.

The object of the present invention is the construction of switchgear whereby the change-over from one busbar to the other can be effected without the use of a plug removable from the casing and without adopting any special construction of the main oil-break switch.

This is accomplished according to the present invention by providing in combination with the movable or draw-out portion of the gear, switches or other connectors whereby either of the busbars or both of them can be joined to the main switch, such switches or connectors being contained within the hood or casing of the movable portion and operated from the outside

thereof without the removal of the switch or connector from the hood or casing.

In one construction of switchgear according to this invention the usual busbar plug connections on the movable draw-out portion are provided inside the hood or casing with clips or other contacts adapted to be engaged by a switch arm mounted on a shaft inside the casing and capable of being rocked or turned say by a lever or by a worm and worm wheel outside the casing. This switch may be connected to one side of the main oil switch and the mechanism operating it can be interlocked with the main switch operating mechanism and if desired with a separate busbar coupling switch. The switch arm or blade may however be so shaped that before leaving one busbar clip or contact it makes connection with the other and in this case the change-over switch functions also as a busbar coupler.

Instead of the one switch arm two may be employed the operating mechanism being such that each arm may be brought into connection with either of the busbar contacts. The two arms may conveniently be mounted on a common pivot and arranged so that they make connection with opposite sides of the busbar contacts. Thus both arms may be in position simultaneously on one busbar contact. In such a construction the operating gear may be of such a nature that the two arms are moved in a convenient sequence. For instance if an earthed contact be provided at each limit of motion of the arms the sequence may be:

1. Both arms move from an earthed contact to No. 1 busbar contact.
2. One arm moves to No. 2 busbar contact thus coupling the busbars.
3. The other arm moves to No. 2 busbar contact thus completing the change-over without breaking the circuit.
4. Both arms move to the second earthed contact.

If the switchgear is intended to work with such a sequence of movement the operating gear may comprise a rotatable disc with pins or studs engaging one or more cam sectors or quadrants shaped so as to

produce the required pause or dwell in the movements of the arms. Each sector may be operatively connected to its contact arm by an insulating link or coupling.

5 In another construction the change-over switch arms, instead of being pivoted are arranged to move vertically in the casing. In this form one end of each arm may be in permanent sliding contact with a bar or rod connected to one side of the main oil-break switch and the vertical motion thus brings the arm into connection with the selected busbar contact or with an earthed contact if such be provided and connects such contact with the oil-break switch.

10 Again the switch arms may have a rotary motion and when in the required position may connect the busbar clips or other contacts with similar contacts on a bar or rod connected to one side of the oil-break switch.

15 Although the change-over connectors are preferably in the form of switches, plug connectors may be employed so long as they are contained within the casing and are operable from the outside thereof without removing them from the casing. For instance plug connectors may be mounted on parallel sliding insulated bars moved by 20 a rack and pinion or by other suitable mechanism.

25 In all the constructions earthed contacts may be provided and interlocking mechanism arranged between the switches or other change-over connectors and the main switch and also between the change-over connectors and the busbar coupling switches if such separate switches are used.

30 The improved construction of switch-gear according to this invention affords opportunity for the convenient and efficient oil-immersion of the change-over switches and other connections inside the hood or casing of the movable portion.

35 In the accompanying drawings,

Figure 1 is a sectional elevation of one construction of switchgear according to this invention,

40 Figure 2 is a diagram of an interlocking circuit connection,

45 Figure 3 is a view similar to Figure 1 but showing a modified construction providing for the operation of the switches in a certain sequence.

50 Figure 4 is a separate view of a portion of Figure 3,

55 Figure 5 is a sectional elevation of another construction also according to this invention,

60 Figures 6 and 7 are respectively a sectional elevation and plan of a modified construction, and

65 Figure 8 is a sectional elevation of another construction.

All the figures are largely diagrammatic,

constructional details not essential to the understanding of the invention being omitted.

70 Figures 1, 3, 4, 5, 6, 7 and 8 show only the movable or draw-out portion of the switchgear which in each case comprises a hood or casing A, socket connections B and B¹ which, when the draw-out portion is racked in, make connection with duplicate busbars, and a third socket connection C 75 joined to one side of an oil-break switch not shown, but contained in a tank beneath the base plate A¹. As these features are known in themselves and are common to all the figures above mentioned, they are 80 lettered similarly and their detail construction is not described.

85 With more particular reference to the construction shown in Figure 1, the upper busbar socket connection B is furnished inside the casing A with a contact plate B² and the lower busbar connection B¹ with a contact plate B³. Within the casing is a switch arm D connected to the other pole 90 of the main oil break switch and this switch arm D is mechanically connected by an insulating link E and crank F to a shaft G which passes through the wall of the casing A and can be partially rotated by means of a crank H, connecting rod H¹ and crank H² through worm gear H³. By suitable movement of this gear the switch arm D can be caused to take up three positions, (1) that shown in full lines where the busbar connection B¹ is joined to the oil break 100 switch, (2) that shown in chain lines where the busbar connection B is similarly connected, and (3) that shown in dotted lines where the switch arm D makes contact with an earthing connection J and the main 105 switch is consequently earthed.

110 In this construction the contact member D¹ carried by the switch arm D is shown as broad enough to bridge the space between the contact plates B² and B³ so that connection is made with one of those plates before connection is broken with the other. Thus the switch D may act as a busbar 115 coupler as well as a change-over switch, although in practice a separate busbar coupler switch would usually be employed.

120 It is preferred to provide some convenient form of interlocking mechanism to prevent the movement of the change-over switch until conditions are suitable for such movement. Such interlock, for instance, may be between the main oil-break switch or the movable portion of the gear carrying it, and the change-over switch D and any known form of mechanical or electrical interlocking mechanism may be thus used. By way of example only an electrical interlock is shown in Figure 1 where the shaft G is provided with a fixed collar G¹ having 125 holes or recesses G² to receive a pin K¹ on 130

the armature of an electromagnet K. Only two holes are shown but obviously a third hole might be provided corresponding to the position of the switch arm D when on the earthing connection J. The winding of the electromagnet K is connected to contact plugs L and L¹ carried on the movable portion of the switchgear and cooperating respectively with sockets M and M¹ on some fixed portion of the gear. One arrangement of the interlocking circuit is shown in the diagram forming Figure 2. In this figure two busbars are indicated at N and N¹ having fixed plugs N² and N³ operating, when the movable portion and its casing A are racked in, with the socket connections B and B¹. The fixed sockets M¹ are connected in a local circuit comprising a battery O and push switch O¹ and when the movable portion of the gear is racked out into the position shown, the interlocking electromagnet K can be energized by closing the push switch O¹ so that the pin K¹ is disengaged from the shaft G which can then be partially rotated to move the switch arm D as may be desired. In Figure 2 the main oil-break switch is indicated at X and separate busbar coupling switchgear P is shown having busbar sockets P¹ and P² on its movable portion and draw-out plug and socket connections P³ forming part of a local circuit including a battery O² and push switch O³ and also including the fixed sockets M cooperating with the plugs L. This local circuit is controlled by an auxiliary switch P⁴ closed only when the coupler switch P is closed and thus the local circuit O² O³ etc. can, when the plugs L and sockets M are connected and the coupler switch P is closed, be completed by the push switch O³ to release the shaft G and allow the change-over switch D to be moved. As previously mentioned this interlocking arrangement is merely given by way of example and may be varied in many ways which are known in connection with switchgear of this general type. Figures 3 and 4 illustrate another construction of change-over switch according to this invention in which the two switch arms D² and D³ are pivoted side by side and can be moved in a definite sequence. The switch arm D² is mechanically connected by an insulating rod D⁴ to a pivoted sector plate D⁵ forming part of a Geneva stop mechanism. The other switch arm D³ is similarly connected through a rod D⁶ to another sector plate D⁷. The sector plate D⁵ is driven by pins R¹ in a disc R (Figure 3) and the plate D⁷ by pins R² in another disc R² (Figure 4), the discs being mounted on a shaft rotatable by any suitable gear. This gear is not shown but it may, for instance, be similar to the gear illustrated in Figure 1 for par-

tially rotating the shaft G. The teeth on the sector plate D⁵ and D⁷ and the pins R¹ and R² engaging them are so arranged that the switch arms D² and D³ may be moved to take up the following positions:—

1. Both arms on an earthing contact J¹.
2. Both arm move from the earthing contact J¹ to the top busbar connection B⁴.
3. Arm D² advances to lower busbar connection B⁵, arm D³ remaining on B⁴. This is the position shown in Figure 3 and the two busbars are then coupled.
4. Arm D² remains on busbar connection B⁵ and arm D³ advances to the same busbar connection.
5. Both arms advance to a bottom earthing contact J².

From this last position the sequence of operations may be reversed by turning back the shaft on which the discs R and R² are mounted. Obviously either or both of the earthing contacts may be omitted if desired.

The details of construction of the Geneva stop work constituted by the pin discs and sector plates need not be described in detail as mechanism of this type which act to give a pause or dwell in the movement of the driven member are well-known in themselves.

In Figure 5 the change-over switches are shown in the form of two blades D⁸ and D⁹ mounted on a rod D¹⁰ which can be moved up and down in the hood or casing A to connect either of the busbar connections B and B¹ with a common bar or rod D¹¹ joined to one pole of the main oil-break switch. An earthing connection is shown at J³ on to which the lower blade D⁹ may be carried to earth the oil-break switch.

Figures 6 and 7 illustrate a modified construction in which the switch arms D¹² and D¹³ are mounted on concentric rotatable shafts D¹⁴ and D¹⁵ so that they may be moved to join either busbar connection B or B¹ to a rod D¹⁶ joined to the main oil-break switch, or to earth that switch by connecting it to an earthing contact J⁴.

Figure 8 shows the change-over switches in the form of plug contacts D¹⁷, D¹⁸ carried on bars or rods D¹⁹, D²⁰ moved by racks D²¹ and D²² and a pinion D²³ into and out of connection with the busbar contacts B and B¹. The bars D¹⁹ and D²⁰ make connection with the rod D²⁴ joined to the main oil-break switch.

As in the other constructions an earthing connection may be provided.

For convenience both racks D²¹ and D²² are shown as operated by one pinion D²³ but obviously the racks may be driven separately and would be so driven if the gear were intended for use as a busbar coupler as well as a change-over switch.

For the sake of clearness the various constructions have been illustrated and de-

scribed with reference only to one phase of the switchgear, but obviously in, for instance, three-phase switchgear, each phase may be provided with the change-over switches described and the operating gear may be linked or coupled in any known way so that the switches for the three phases operate together.

It is to be understood that the constructions illustrated are intended to be examples of various forms which the improved switchgear according to this invention may take. The feature common to them all is that the change-over switch is contained in the hood or casing of the movable portion of the gear and can be operated by suitable mechanism from outside that casing.

What I claim as my invention and desire to secure by Letters Patent is:—

20 1. In electric switchgear of the metal-clad horizontal draw-out type for a duplicate busbar system, the combination with the movable or draw-out portion of the switchgear, of a main switch, a hood or casing carried by said movable portion, duplicate busbar connections mounted on said casing, at least one switch arm or connector within the casing adapted to connect either of said busbar connections to one pole 25 of the main switch, and means outside the casing for operating said switch arm or connector.

30 2. In electric switchgear of the metal-clad horizontal draw-out type for a duplicate busbar system, the combination with the movable or draw-out portion of the switchgear, of a main oil-break switch, a hood or casing carried by said movable portion, duplicate busbar connections mounted on said casing, at least one pivoted switch arm within the casing in electrical connection with one pole of the main switch and adapted to be brought into contact with either of said busbar connections, and mechanism operated 35 from outside the casing for moving said pivoted switch arm.

40 3. In electric switchgear of the metal-clad horizontal draw-out type for a duplicate busbar system, the combination with the movable or draw-out portion of the switchgear, of a main oil-break switch, a hood or casing carried by said movable portion, duplicate busbar connections mounted on said casing, two pivoted switch arms within the casing in electrical connection with one pole of the main switch and adapted to be brought into contact with either of said busbar connections, and mechanism operated 45 from outside the casing for moving said pivoted switch arms in a definite sequence into and out of contact with the busbar connections.

50 4. In electric switchgear of the metal-clad horizontal draw-out type for a duplicate busbar system, the combination with the

movable or draw-out portion of the switchgear, of a main oil-break switch, a hood or casing carried by said movable portion, duplicate busbar connections mounted on said casing, an earthing connection within the 55 casing, at least one switch arm or connector within the casing adapted to connect either of said busbar connections or said earthing connection to one pole of the main switch, and means outside the casing for 60 operating said switch arm or connector.

5. In electric switchgear of the metal-clad horizontal draw-out type for a duplicate busbar system, the combination with the movable or draw-out portion of the switchgear, of a main oil-break switch, a hood or casing carried by said movable portion, duplicate busbar connections mounted on said casing, an earthing connection within the 65 casing, at least one pivoted switch arm within the casing in electrical connection with one pole of the main switch and adapted to be brought into contact with either of said busbar connections or with said earthing connection, and mechanism operated 70 from outside the casing for moving said pivoted switch arm.

6. In electric switchgear of the metal-clad horizontal draw-out type for a duplicate busbar system, the combination with the movable or draw-out portion of the switchgear, of a main oil-break switch, a hood or casing carried by said movable portion, duplicate busbar connections mounted on 75 said casing, an earthing connection within the casing, two pivoted switch arms within the casing adapted to connect either of said busbar connections or said earthing connection to one pole of the main switch, and mechanism operated 80 from outside the casing for moving said pivoted switch arms into and out of contact with the busbar connections.

7. In electric switchgear of the metal-clad horizontal draw-out type for a duplicate busbar system, the combination with the movable or draw-out portion of the switchgear, of a main oil-break switch, a hood or casing carried by said movable portion, duplicate busbar connections mounted on 85 said casing, two pivoted switch arms within the casing in electrical connection with one pole of the main switch and adapted to be brought into contact with either of said busbar connections, a shaft within the casing 90 and extending outside thereof, operative connections between said shaft and said switch arms, and means outside the casing for rocking said shaft.

8. In electric switchgear of the metal-clad horizontal draw-out type for a duplicate busbar system, the combination with the movable or draw-out portion of the switchgear, of a main oil-break switch, a hood or casing carried by said movable portion,

duplicate busbar connections mounted on said casing, two pivoted switch arms within the casing in electrical connection with one pole of the main switch and adapted to be brought into contact with either of said busbar connections, a shaft within the casing and extending outside thereof, operative connections between said shaft and said

switch arms, means outside the casing for rocking said shaft, and interlocking means for preventing the rocking of said shaft until the conditions are suitable. 10

In testimony whereof I have signed my name to this specification.

JAMES MIRREY.
